Inventor:
Edwin A. Borden

By: Robert F. Miehle, Jr. Atty.

UNITED STATES PATENT OFFICE.

EDWIN A. BORDEN, OF OAK PARK, ILLINOIS.

MEANS FOR THE TREATMENT OF PRINTING PLATES.

Application filed November 9, 1923. Serial No. 673,775.

My invention relates particularly to means for building up or leveling the printing faces of printing plates by the application of pressure, preferably while the plates are heated to a plastic condition, to the plates, the means of my invention effecting the conformation of the printing faces of the printing plates without exerting excessive pressure on localized portions of the plates whereby the printing faces thereof are not injured.

Generally speaking my invention consists of a member of non-displaceable material provided with an exposed facewise pattern 15 providing displacement space in combination with a sheet of displaceable material, these members being adapted when subjected to pressure on the back of a printing plate with the sheet of displaceable material in displacing relation with the pattern of the non-displaceable member for building up or leveling the printing face of the printing plate.

By reason of this arrangement it is not necessary to provide a displacement space 25 providing pattern in the sheet of displaceable material thus facilitating the manufacture thereof.

In the preferred practise of the invention the member of non-displaceable material 30 provided with the displacement space providing pattern is capable of re-use whereby it may be used in the treatment of a great number of printing plates, and whereby only the sheet of displaceable material need be 35 replaced or reformed either after the treatment of each printing plate or after treating a number of plates depending on the character of the sheet of displaceable material.

The invention will be more readily understood by reference to the accompanying drawing forming a part of this specification, in which—

Figure 1 is an exaggerated partial sectional view of a printing plate and the means 45 of my invention under pressure between the pressure members of a suitable press.

Figure 2 is a partial face view of the patterned member of my invention.

Figure 3 is a sectional view of the means 50 of my invention showing the various members spaced apart for purposes of clarity.

Like characters of reference indicate like parts in the several views.

In the said drawings, 1 and 2 designate 55 respectively the upper and lower pressure members of a suitable press, and 3 designates

a printing plate of the type commonly known as an electrotype plate. As shown the patterned member consists of a flexible sheet 4 of non-displaceable material, such as copper or other metal or material which will flex or yield without bodily distortion, and having a solid central portion on one or both faces of which are formed uniformly spaced apart uniform disk-like projections 5 forming exposed displacement space providing facewise patterns at both faces of the sheet 4. The sheets of displaceable material are designated at 6.

In the treatment of a printing plate the sheet 4 is interposed between two sheets 6 and the sheets 4 and 6, so arranged, are subjected to pressure on the back of the printing plate 3 between the pressure members 1 and 2 of the press, the pressure being preferably exerted with the plate heated to render the same plastic such as by heating either the upper pressure member 1 or both of the pressure members 1 and 2. A temperature of approximately 199° C. is sufficient.

The sheets 6 are of suitable thickness such as one-eighth of an inch and may be of any suitable displaceable material which is capable of bodily distortion under inequalities of pressure, and as examples vulcanized rubber composition or a mixture of 64 per cent asphaltum, 35 per cent fixed oil such as linseed, castor, cottonseed, maize, or China wood oil, and 1 per cent dryer of the usual type is proposed for the treatment of the printing plates heated to a plastic condition.

When the pressure is exerted by the press upon the printing plate 3 and the sheets 4 and 6 the sheets 6 displace more or less into the displacement space providing patterns of the sheet 4 to build up or level the printing face of the plate by conforming the same with the opposing pressure member 1 without exerting excessive pressure upon any portion of the plate whereby the printing face of the plate is not injured. The varying displacement of the sheets 6 is clearly shown in Fig. 1 in which 7 designates a relatively thick portion of the plate 3 under which the sheets 6 have been displaced to a greater extent than under the thinner portions of the plate. By reason of the fact that the sheet 4 is flexible the effect of the sheet 6 against the lower pressure member 2 is exerted on the plate 3, and it will be observed that by this arrangement double the displacing effect of one sheet 6 is provided.

which is of considerable advantage in many instances, though a single sheet 6 may be used effectively in many instances in which case one series of projections 5 does not function with respect to sheet 6 but acts to transmit the pressure.

In the re-use of the sheet 4 the displaced sheets 6 are removed and new sheets 6 substituted as often as may be necessary depending upon the character of the sheets 6.

Thus it will be observed that a practical, effective, and economical means of the character described is provided which permits of the re-use of the patterned member and which permits plain sheets 6 being used with resultant ease and economy of manufacture thereof.

By the use of the term printing plate or plate I do not limit myself to an integral printing plate as the invention is adapted to type and cut forms, but use the term in a general sense as meaning any type of printing plate or printing form.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a means for the treatment of printing plates the combination of a member of non-displaceable material provided with an exposed facewise pattern providing displacement space, and a sheet of displaceable material, said member and sheet being adapted when they are subjected to pressure on the back of a printing plate with the sheet in displacing relation with said pattern for building up or leveling the printing face of the printing plate.

2. In a means for the treatment of printing plates the combination of a flexible sheet of non-displaceable material capable of re-use and patterned in a face thereof to provide displacement space, and a sheet of displaceable material, said sheets being adapted when they are subjected to pressure on the back of a printing plate with the second mentioned sheet against the aforementioned face of the first mentioned sheet for building up or leveling the printing face of the printing plate.

3. In a means for the treatment of printing plates the combination of a flexible sheet of non-displaceable material capable of re-use and patterned in both faces thereof to provide displacement space, and two sheets of displaceable material, said sheets being adapted when they are subjected to pressure

on the back of a printing plate with the first mentioned sheet interposed between the second mentioned sheets for building up or leveling the printing face of the printing plate.

4. In a means for the treatment of printing plates the combination of a member of non-displaceable material provided with an exposed facewise pattern providing displacement space, and a sheet of displaceable material, said member and sheet being adapted when they are subjected to pressure on the back of a printing plate with the sheet in displacing relation with said pattern and with the printing plate heated to render the printing plate plastic to build up or level the printing face of the plate.

5. In a means for the treatment of printing plates the combination of a member of non-displaceable material capable of re-use and patterned in a face thereof to provide displacement space, and a sheet composed of a mixture of 64 per cent asphaltum, 35 per cent fixed oil and 1 per cent dryer, said member and sheet being adapted when they are subjected to pressure on the back of a printing plate with said sheet against the aforementioned face of said member and with the printing plate heated to render the printing plate plastic to build up or level the printing face of the plate.

6. In a means for the treatment of printing plates the combination of a flexible sheet of non-displaceable material patterned in both faces thereof to provide displacement space, and two sheets of displaceable material, said sheets being adapted when they are subjected to pressure on the back of a printing plate with the first mentioned sheet interposed between said second mentioned sheets and with the printing plate heated to a temperature at which the printing plate is plastic to build up or level the printing face of the plate.

7. In a means for the treatment of printing plates the combination of a flexible metal sheet patterned in both faces thereof to provide displacement space, and two sheets composed of a mixture of 64 per cent asphaltum, 35 per cent fixed oil and 1 per cent dryer, said sheets being adapted when subjected to pressure on the back of a printing plate with the first mentioned sheet interposed between said second mentioned sheets and with the printing plate heated to a temperature at which the printing plate is plastic to build up or level the printing face of the plate.

In witness whereof I hereunto affix my signature this seventh day of November, 1923.

EDWIN A. BORDEN.
